UNITED STATES PATENT OFFICE.

PETER C. REILLY, OF INDIANAPOLIS, INDIANA.

PAVEMENT.

No. 829,294.

Specification of Letters Patent.

Patented Aug. 21, 1906.

Application filed March 30, 1904. Serial No. 200,736.

To all whom it may concern:

Be it known that I, PETER C. REILLY, a citizen of the United States, residing at Indianapolis, Indiana, have invented a certain new and useful Improvement in Pavements; and I do hereby declare the following to be a full, clear, and exact description of the invention, such as will enable others skilled in the art to which it appertains to make and use the same.

This invention relates to pavements, and particularly to wearing-surfaces.

The object of the invention is the provision of a wearing-surface having great stability and durability, affording a secure foothold, and requiring comparatively small tractive force.

A difficulty encountered in the construction of pavements exposed to the action of the elements is the liability to deterioration caused by the absorption of water and uneven wear, due to inequalities in density of the material in the structural composition. Bituminous pavements, whether of asphalt or other kinds of bitumen or whether a combination of bitumen with other substances, must in order to produce the best results be compact and free from voids, and that pavement which is nearest free from voids is in that degree the best pavement. Bituminous pavements as heretofore laid contain a large percentage of voids, and this is true whether the bitumen be used in connection with sand or with broken stone or other material. The result of this condition is that the pavement is not at all points stable and self-supporting; but when it becomes heated by atmospheric influences or by the friction incident to traffic it does not maintain its original position and creeps toward the lower points of the street and forms in waves transverse to the direction of traffic. A further result is that on account of the uneven distribution of the voids in the pavement the pavement is more easily compressed at some points than at others by the pressure of traffic, thus making an uneven surface, which after a time by the effect of the traffic forms waves, as above indicated. The defective condition of bituminous pavements above set out is the result of the unscientific method of construction heretofore practiced. The bituminous pavement, commonly known as "asphalt pavement," is constructed with an asphaltic cement, usually formed of asphaltum-pitch and sand. This cement while in a heated condition is spread upon

the surface of the street and by a process of compression or rolling fixed in position, the compression being intended to so compact the cement as to make it one solid mass free from voids; but it has never been found possible by such a process to entirely eliminate the voids.

Another method of constructing bituminous pavements has been used whereby the wearing-surface of the pavement is constructed by taking predetermined proportions of broken stone of different sizes so proportioned that when uncoated with pitch they may be settled into a mass having a small percentage of voids. This character of stone is then coated with bitumen, spread on the street, and compacted by a process of rolling. As a laboratory test it is possible to take uncoated broken stone of predetermined proportions of different sizes and by a process of vibration settle them into a mass whereby the percentage of voids will be small; but the same character of stone when coated with pitch and dumped and spread on a street and then compacted by rolling will not assume that perfect condition that it can be placed in by laboratory manipulation, and the result is that the pavement is imperfect and not free from voids. It shows, therefore, the same defects after use as are found in the ordinary sheet-asphalt pavement, which are brought about in the same way.

It is impossible by the methods of compression above set out to take the materials above described and form them into a compact pavement free from voids. I have found that the only practical method by which a bituminous pavement can be laid so as to be free from voids is by taking a quarry run of stone, preferably from one inch down, and mixing it with sufficient proportions of sand and bitumen so as to make a dense mortar while in a heated state. If such a mortar be dumped and spread on a street, the bitumen and sand, being of a more fluid nature than the stone, will flow at once to the bottom. Then by a process of tamping and rolling the particles of stone may be forced downward, and by a process of displacement the mortary substance will be brought to the surface. This mortary substance will not rise to the surface so long as there are any voids which it may seek toward the bottom of the coat of mortar, and therefore all voids will be filled before it will rise, so that if the tamping and rolling process is carried on to a time when

the mortary substance has risen to the top the whole will be free from voids. It may be suggested in criticism of my statements above that the same process of tamping 5 would produce a solid mass in an asphalt pavement or in the other bituminous pavement above described; but such is not the case. In the asphalt pavement as heretofore laid the substance when put upon the 10 street is not a mortary substance, but is composed of asphaltum-pitch and sand which is all practically of the same size in its particles, and when the process of tamping and rolling is resorted to, the mass being all of a 15 similar character and consistency, there is no fluid substance at the bottom to be displaced and forced to the top by the process of tamping and rolling; neither is there any mortary substance in the other bituminous pave- 20 ment above described which can flow to the top when a process of tamping and rolling is resorted to. More briefly stated, the producers of asphalt pavement rely upon the process of compression to produce a solid 25 mass, the producers of the other bituminous pavement above described rely upon the intermixing of different sizes of stone in pre-determined proportions, and I rely upon the mortary substance which flows to the bot- 30 tom of the pavement and is projected upward by a method of displacement caused by the process of tamping and, as above set out, cannot be forced upward so long as there may be any voids for it to seek in the lower part of 35 the pavement.

All the difficulties above noted are overcome and the desirable objects above noted are attained in the wearing-surface forming the subject of the present invention and the 40 application for a patent thereon.

An embodiment of the invention is illustrated in the accompanying drawing, which represents a cross-section of a piece of pavement constructed in accordance therewith.

45 In this drawing, *a* represents the curb, *b* the foundation structure, and *c* the wearing-surface.

In producing a pavement of this character the concrete foundation *b* is laid in the usual 50 manner, swept, and a coating of cement (preferably National brand bituminous cement No. 1) is applied thereto. The structure is then ready for the application of the wearing-surface, which is prepared as fol-

55 lows: The natural run of crushed granite or other suitable stone varying in size from one and three-fourths inches or any other selected size downward is mixed with sufficient clean, sharp, coarse sand and bituminous 60 cement (preferably National bituminous cement No. 2) to make the whole a dense mortary substance. The crushed stone and sand before being mixed with the cement are heated to a temperature of approximately 65 250° Fahrenheit. The bituminous cement is

heated approximately to the same tempera- 7c ture. The resultant mass is mixed until each particle of stone and sand is thoroughly coated with the cement. This wearing-surface mixture is now added to the foundation to a depth of approximately three inches. It is thoroughly tamped and rolled in such manner as to bring to the top the mortar forming the more fluid portion of the mass, producing a quick-setting smooth surface. 75 The depth of the wearing-surface after tamping and rolling should be about two and one-half inches. The pavement thus produced is ready for almost immediate use and has been found to be impervious to moisture, 80 stable and fixed in character, of long life, and it requires a minimum of expenditure for repairs and renewals because of its firmness and fineness of texture.

By using a smaller proportion of the mor- 85 tary substance it will not rise high enough to make the top of the pavement entirely smooth, but will leave the larger particles of the stone slightly protruding from the surface, thus forming a pavement with a rough sur- 90 face very necessary and useful on inclines and where there is heavy drawing.

Wherefore, having thus fully disclosed my invention, what I claim as new, and desire to secure by Letters Patent of the United States, is—

1. A wearing-surface for pavements comprising a concrete mass, of which the larger component particles form the lower part, and the finer particles fill the interstices between 100 the larger particles and form a smooth upper surface, whereby is formed a wearing-surface containing stones decreasing in size from the bottom toward the top.

2. A wearing-surface for pavements, com- 105 prising a bituminous concrete mass of constituents decreasing in size from the bottom toward the top, the finer particles filling the voids between the larger particles and forming a smooth upper surface.

3. The method of producing a wearing-surface for pavements which consists in preparing a mortary mass, forcing the smaller particles into the interstices from the bottom toward the top and above the larger stone 115 particles and allowing it to set, whereby is formed a wearing-surface containing stones decreasing in size from the bottom toward the top.

4. The method of producing a wearing-surface for pavements, which consists in applying bituminous concrete as a mortary mass, tamping or rolling until the finer particles fill the voids and interstices of the larger particles and are largely brought above the larger 125 particles to the top as a semiliquid mortar, and allowing it to set, whereby is formed a wear- ing-surface containing stones decreasing in size from the bottom toward the top.

5. The method of producing a wearing-surface 130

face for pavements, which consists in adding to the natural run of broken stone, twenty per cent. of sand and ten to fifteen per cent. of bituminous cement, applying as a dense mortary mass to the foundation, and tamping or rolling until the finer particles are forced into the voids and largely brought above the larger particles to the top as a semiliquid mortar, and allowing it to harden, whereby is formed a wearing-surface containing stones decreasing in size from the bottom toward the top.

6. The method of producing a wearing-surface for pavements, which consists in preparing a dense mortary mass of stone, sand and

bituminous cement, applying the mass to a suitable foundation, tamping or rolling until the larger stone particles are forced to the bottom displacing toward the top the semi-liquid portion to fill the interstices and form a smooth upper surface, and allowing to harden.

In testimony whereof I affix my signature to this specification in the presence of two witnesses.
